(57) **CLAIM**

The ornamental design for a cam follower, as shown and described.

DESCRIPTION

FIG. 1 is a perspective view of a first embodiment of a cam follower, showing our new design;

FIG. 2 is a front view of the first embodiment of the cam follower;

FIG. 3 is a rear view of the first embodiment of the cam follower;

FIG. 4 is a top view of the first embodiment of the cam follower;

FIG. 5 is a bottom view of the first embodiment of the cam follower;

FIG. 6 is a left view of the first embodiment of the cam follower;

FIG. 7 is a right view of the first embodiment of the cam follower;

FIG. 8 is a perspective view of a second embodiment of the cam follower;

FIG. 9 is a front view of the second embodiment of the cam follower;

FIG. 10 is a rear view of the second embodiment of the cam follower;

FIG. 11 is a top view of the second embodiment of the cam follower;

FIG. 12 is a bottom view of the second embodiment of the cam follower;

FIG. 13 is a left view of the second embodiment of the cam follower;

FIG. 14 is a right view of the second embodiment of the cam follower;

FIG. 15 is a perspective view a third embodiment of the cam follower;

FIG. 16 is a front view of the third embodiment of the cam follower;

FIG. 17 is a rear view of the third embodiment of the cam follower;

FIG. 18 is a top view of the third embodiment of the cam follower;

FIG. 19 is a bottom view of the third embodiment of the cam follower;

FIG. 20 is a left view of the third embodiment of the cam follower; and,

FIG. 21 is a right view of the third embodiment of the cam follower.

(Continued)

The broken lines showing in the figures are included for the purpose of illustrating portions of the cam follower that forms no part of the claimed design. The dot-dash broken lines represent the bounds of the claimed design and form no part thereof. The cam follower is shown with symbolic breaks in its length in FIGS. 15-19. The appearance of any portion of the cam follower between the break lines forms no part of the claimed design.
